UNITED STATES PATENT OFFICE.

JOHN GIDEON KIRKSEY, OF CARTHAGE, MISSOURI.

ORE-SEPARATOR.

No. 833,223.

Specification of Letters Patent.

Patented Oct. 16, 1906.

Application filed September 23, 1903. Serial No. 174,331.

To all whom it may concern:

Be it known that I, JOHN GIDEON KIRKSEY, a citizen of the United States, residing at Carthage, in the county of Jasper and State 5 of Missouri, have invented a new and useful Ore-Separator, of which the following is a specification.

My invention relates to ore-concentrators, and especially to devices of this character in 10 which the ore is washed over the surface of a transversely-inclined vibratory table and separated by gravity into strata of varying degrees of purity, and has for its objects to provide a device of this character of comparatively simple construction which will be efficient in operation, one in which a steady uniform vibration is imparted to the table, and one in which the degree of inclination of the 15 table and the speed of vibration thereof may be regulated at will to accord with the nature of the material under treatment.

To these ends the invention comprises the novel details of construction and combination of parts more fully hereinafter described.

25 In the accompanying drawings, Figure 1 is a perspective view of an ore-concentrator embodying my invention. Fig. 2 is a plan view of the same with the table partly broken away to expose the underlying mechanism 30 to view. Fig. 3 is a vertical transverse section through the device. Fig. 4 is a rear elevation.

Referring to the drawings, 1 indicates a main base-frame consisting of longitudinal 35 front and rear beams 2 and 3, respectively, and transverse connecting-beams 4. Mounted upon the main base-frame is a supplemental frame consisting of lower front and rear longitudinal beams 5 6 and upper front 40 and rear longitudinal beams 7 and 8, which are spaced vertically above the respective lower beams by suitable spacing-blocks 9 and are connected by transverse beams 10. The supplemental frame is hinged at its front longitudinal edge to the base-frame 1 by means 45 of hinges 11, attached to the front bars 2 and 5 of the respective frames, whereby the supplemental frame may be transversely inclined to a greater or lesser degree by raising 50 and lowering its rear side in the manner presently described.

Mounted for longitudinal reciprocation upon the supplemental frame is a table 12, the surface of which is composed of any suitable

material, such as sheet metal or planking, secured to a framework made up of longitudinal front and rear bars 13 and transverse connecting-boards 14, said table having attached to its under side and at its transverse center longitudinal bar 15, while upon the upper surface of the table there is arranged a series of 55 ripples 16, preferably of the form and arrangement herein shown. The forward end and rear longitudinal edge of the table are bordered by an upwardly-extending vertical 60 flange, while the rear end and front longitudinal edge are bordered by vertically-depend- 65 ing flanges, said flanges all consisting, preferably, of sheet metal. There is also mounted at the rear longitudinal edge of the table a 70 pipe 17, which is suitably perforated and de- 75 livered upon the table during the concentrat- 80 ing operation a constant stream of water, and at the rear of the table, adjacent to its front end, there is mounted a box or hopper 75 85 18, which receives the ore or other material to be treated and delivers the same onto the table.

My improved mechanism for reciprocating the table 12 to impart a vibratory motion 80 thereto consists of a crank-shaft 19—journaled in bearings sustained by brackets 20, at- 85 tached to the transverse beams 4-10 at the forward end of the machine. The shaft has a suitable crank-bend 21, within which is 90 journaled one end of a link 22, the opposite end of which is pivoted to the end of a recip- 95 rocating pitman 23, slidably mounted in bearings 24, sustained by the transverse beams of the supplemental frame. The pit- 100 man 23 is composed of two sections disposed end to end in parallel relation, the adjacent ends of the sections being oppositely thread- 105 ed, or, in other words, having, respectively, right and left hand threads and connected by a turnbuckle or member 25, which may be manipulated for lengthening or shortening the pitman, as will be readily understood, and for the purpose which will later appear.

A pair of lazy-tong levers 26 are pivoted, 100 as at 27, to one of the transverse beams 10, said levers being provided at their forward ends with suitable heads or blocks 28, pro- 105 vided with lateral horizontal sockets, and at their rear ends with similar socketed heads or blocks 29, in which are pivoted the forward ends of a pair of links 30, the opposite ends of which are pivoted in the head 31 of a pitman.

32, slidingly mounted in bearings 33, sustained by the transverse beams of the supplemental frame. The rear end of pitman 32 extends through the vertically-dependng 5 portion of an angle-plate 34, bolted or otherwise secured to the under side of bar 15, and has its end threaded for the reception of a suitable nut 35, whereby the active portion of the pitman 32 may be varied. Disposed 10 upon the shaft 32 is a normally expanded spring 36, which bears at one end upon the forward bearing 33 and at its opposite end upon an adjusting-nut 37, which is tapped on to the pitman and may be manipulated for 15 varying the tension of the spring. 38 is a pair of links each of which has one of its ends seated loosely in one of the sockets of head 28, the other ends of the links being seated loosely in sockets formed in a head 39, provided upon the rear end of pitman 23.

In practice rotary motion is imparted to shaft 19 from any suitable source of power and serves, through the medium of link 22, to reciprocate pitman 23, which in turn acts, 25 through the medium of links 38, to spread or expand the front ends of the lazy-tongs 26 at every forward stroke of the pitman. This action likewise spreads the rear ends of the lazy-tongs and through the medium of links 30 and pitman 32 imparts a rapid forward reciprocation to the table, the spring 36 being at the same time compressed. Upon each rearward stroke of pitman 23 the forward ends of the lazy-tongs are relieved of 35 the expanding pressure of links 38, whereby the spring 36 is permitted to expand and in expanding causes a rearward stroke of the table through the medium of pitman 32, while at the same time the pull exerted upon 40 links 30 moves the ends of the lazy-tongs inward to maintain them in engagement with the links 38. Attention is here directed to the fact that the expanding force or movement of spring 36 is less than the speed of 45 movement of pitman 23, whereby the table is reciprocated fore and aft with an alternating quick and slow movement, the movement in one direction being rapid and that in the other being comparatively slow, whereby a 50 vibratory shock will follow at the end of each movement of the table, which will serve to feed the material bodily forward longitudinally thereof, at the same time acting to separate or concentrate the material, as will be 55 readily understood. It is also to be noted that the tension of spring 36 may be readily varied as circumstances require for regulating the movement of the table, thereby to accord with the movement imparted from pit- 60 man 23.

It will be noted that the links 38 fit at their ends within sockets and do not require fastening means, such as pivot-pins, because the spring 36 causes the ends of the levers 26 to 65 press against the links at all times. Wear

upon the links is thus taken up automatically and there is no danger of the mechanism getting out of order at this point.

The travel of table 12 is rendered smooth and frictionless by means of balls or other 70 antifriction devices 40, disposed between bearing-plates arranged at intervals throughout the length of the table and provided with suitable raceways for the antifriction devices.

As before stated, the table 12 is inclined 75 transversely, and for maintaining and varying said inclination I employ at the rear side of the device a horizontal longitudinally-disposed shaft 41, provided at intervals with head-blocks 42, in each of which are pivoted 80 the ends of a pair of links 43, the outer ends of said links being pivoted, respectively, to the longitudinal bar 3 of the main frame and the upper longitudinal bar 8 of the supplemental frame. There are preferably three sets of 85 links 43, disposed, respectively, adjacent to the ends and longitudinal center of the frame, said links being simultaneously expanded or contracted for raising or lowering the supplemental frame at its rear side relative to the 90 base-frame 1 by moving the shaft 41 in a longitudinal direction. This motion is imparted to the shaft by means of a screw 44, operatively connected with the forward end 95 of the shaft and working in a movable bearing 45, the end of said screw being provided with a hand-wheel 46, whereby it may be rotated for operating the shaft. From this construction it will be seen that when the hand-wheel is rotated in one direction it will 100 move the shaft 41 forwardly and longitudinally of the frame, thus expanding the links 43 and raising the supplemental frame at its rear side for inclining the table 12 forwardly 105 transversely, whereas movement in the other 110 direction contracts the links and decreases the inclination of the table. Thus it will be seen that the inclination of the table may be readily varied or regulated according to the 115 nature of material under treatment.

In operation the ore is delivered at the front upper side of the table and is washed transversely across the same. As the ore travels over the table it is separated, owing 120 to its varying specific gravity, into strata which form in the spaces between the riffles 16, the heavier particles settling, of course, at the highest point of the table, those of a lighter character at a lower point, &c., until the gangue washes over the lower edge of the 125 table. After this primary separation the ore moves longitudinally of the table, owing to the vibration of the latter, and is delivered at the rear discharge end of the table in a thoroughly-separated condition, the degree of the vibration of the table and also its inclination being regulated in the manner heretofore described to meet the conditions and character of the material.

From the foregoing it will be seen that I 130

produce a device of comparatively simple construction by which the ore will be thoroughly separated and one in which there will be imparted to the table during its operation 5 a uniform vibration, thus rendering the separation more perfect, and one in which the degree of vibration may be readily varied, as heretofore explained. In attaining these 10 ends I do not limit myself to the precise details herein set forth, inasmuch as minor changes may be made therein without departing from the spirit of the invention.

Having thus described my invention, what I claim is—

15 In an ore-separator, a supporting-frame, a table movably mounted thereon, crossed levers mounted upon a common pivot extending from the frame, an inner rod slidably mounted upon the frame, a bracket extending from 20 the table and adjustably engaged by the rod,

links pivoted to the rod and to one end of the crossed levers, a longitudinally-adjustable rod slidably mounted on the frame and having a head at one end provided with oppositely-disposed sockets, links having rounded 25 ends loosely seated within said sockets and extending therefrom, the outer ends of the links being seated in sockets in the ends of the crossed levers, a spring surrounding the inner rod and bearing thereagainst to clamp 30 the link between the socketed head and the crossed levers, and means for reciprocating the longitudinally-adjustable rod.

In testimony that I claim the foregoing as my own I have hereto affixed my signature 35 in the presence of two witnesses.

JOHN GIDEON KIRKSEY.
